CLAIM

The ornamental design for a shoe sole, as shown and described.

DESCRIPTION

FIG. 1 is a perspective view of a shoe sole in accordance with my new design.

FIG. 2 is a bottom plan view thereof;

FIG. 3 is a right elevational view thereof;

FIG. 4 is a left elevational view thereof;

FIG. 5 is a front elevational view thereof; and,

FIG. 6 is a rear elevational view thereof.

The broken lines immediately adjacent to the solid lines in FIGS. 1 & 3-6 represent the unclaimed boundary of the design while the broken lines showing the remainder of the shoe sole illustrate the portion of the design that forms no part of the claim.
